UNITED STATES PATENT OFFICE.

HAROLD L. WATSON, OF NEW BRUNSWICK, NEW JERSEY.

HEATING SYSTEM FOR MAMMOTH INCUBATORS.

Application filed February 20, 1922. Serial No. 537,679.

To all whom it may concern:

Be it known that I, HAROLD L. WATSON, a citizen of the United States, and a resident of Highland Park, New Brunswick, county 5 of Middlesex, State of New Jersey, have invented certain new and useful Improvements in Heating Systems for Mammoth Incubators, of which the following is a specification, reference being had to the accompanying drawings.

My invention is more especially adaptable to that class of incubators generally known as "mammoth" incubators which embody a plurality of egg containing sections or 15 compartments arranged in superposed tiers one above the other. Incubators of this class generally embody heat radiating means extending through the several compartments in each tier and connected with a suitable 20 water heating unit through the medium of which warm water is supplied thereto to heat the compartments. It is requisite for the successful operation of such an incubator, that the different compartments be maintained during most of the hatching period 25 at substantially uniform temperatures, and considerable difficulty has been experienced in effecting this result by reason of the fact that when the heated water is drawn from 30 a common source and thence conducted to the several superposed tiers the compartments in the lower tiers are generally found to be cooler than those in the upper tiers.

A principal object of my invention therefore is to provide a heating system adapted for employment in connection with mammoth incubators which is effective to maintain the compartments in the lower tiers of the incubator at substantially the same temperature as those in the upper tiers. A further object of the invention is to so arrange the heating unit and the circulating piping extending therefrom to the incubator that the heated water will pass from the 45 unit to the several tiers in the incubator at different temperatures commensurate with the requirements of each particular tier, thereby enabling the compartments in all of the tiers to be maintained at a substantially uniform degree of heat. A still further object of my invention is to provide a heating unit of novel form and construction particularly adapted for use in connection with heating systems for incubators and 50 embodying means whereby the piping may be readily led therefrom in such manner

that the heated water will be supplied to different parts of the incubator at varying temperatures in accordance with the respective location thereof or supplied to a given 60 point at a suitable temperature.

My invention further includes all of the other various objects and novel features of construction and arrangement hereinafter more particularly specified and described. 65

In the accompanying drawing Fig. 1 is a side elevation partially in fragmentary vertical section of a preferred embodiment of the heating unit; Fig. 2 is a central vertical section thereof on the line 2—2 in Fig. 1 70 looking in the direction of the arrows, and Fig. 3 is a transverse horizontal section thereof on line 3—3 in Fig. 1 looking in the direction of the arrows, while in Fig. 4 I have illustrated a preferred manner of arranging the heating unit and piping in connection with a mammoth incubator having three tiers of compartments, only a portion of the incubator itself being shown. Like numerals are used to indicate similar parts 75 in the several figures.

I have found that when employing a heater of ordinary design in connection with a mammoth incubator comprising a plurality of superposed tiers, the compartments of the lowermost tier have a tendency to become too cold and those of the uppermost tier to become too hot when the heating water is supplied at a temperature to keep the center tier, assuming the incubator to 90 embody three tiers, at substantially the desired temperature. This difficulty probably arises from the fact that the lower tiers give off a certain amount of heat which rises and, impinging on the upper tier, tends to 95 raise the temperature of the latter, and, additionally, as incubators of this class are ordinary placed in rooms or cellars having relatively low ceilings, the upper tier is therefore generally located in a warmer atmosphere than the lower so that when the heating water is supplied to the several tiers at the same temperature there is a considerable difference between the temperature of the compartments in the lower tier and those 100 in the upper.

I therefore prefer, in the carrying out of my invention, to employ a heater of the form best shown in Figs. 1 to 3, and which embodies means for permitting the heating water to be supplied from the same heating unit to the several tiers at different tem- 105 110 115

peratures. To this end my preferred form of heater comprises a preferably substantially circular base 1 having an ash door 2 carrying a draught regulating plate 3. Superimposed upon the base is the body 5 which is substantially circular in horizontal section and closed at the top. This body comprises inner and outer spaced walls 7 and 8 connected at their lower extremities, the space 9 between the walls forming a water heating reservoir and the space 10 within the wall 8 forming the combustion chamber of the heater. Within the upper portion of the base and beneath the combustion chamber are a plurality of suitable grate bars 12 preferably provided with intermeshing gear wheels 13 whereby the bars may be simultaneously agitated by partially rotating the center bar through the medium of a suitable crank in the ordinary manner. A port 15 which forms a smoke flue is provided adjacent the upper rear side of the combustion chamber and an elbow 16 preferably of lighter metal than the walls of the body is secured, as by bolts 17, in such position as to register with the port and provide a convenient point of attachment for the smoke pipe 18 through which the products of combustion are discharged, a fuel door 19 provided with a draught regulating plate 20 being arranged adjacent the upper part of the heater on the front side thereof and communicating with a port extending through the reservoir and through which fuel may be supplied to the upper part of the combustion chamber.

To afford a point of convenient attachment for certain of the pipes of the water circulating system, the outer wall 7 of the body of the heater is preferably formed at one side of the heater with a vertically extending boss or extension 25 having a flat face 26 as best shown in Fig. 3 which is provided with a plurality of vertically spaced, preferably pipe-threaded apertures 28, the uppermost of which is preferably near the top of the heater and the lowermost adjacent the bottom of the reservoir. Conveniently these apertures may be laterally staggered as shown in Fig. 1 or, if desired, may be arranged in the same vertical line, and I preferably arrange the two lowermost apertures 28' in the same horizontal plane. It will be understood that apertures 28, 28' extend entirely through the wall of the heater so that the water contained in the reservoir 9 may freely flow into any pipes threaded in the apertures.

For attaining certain of the objects of my invention, a heater of the character just described may preferably be installed and connected with a mammoth incubator having a plurality, for example, three, tiers of compartments in the manner best shown in Fig. 4 and which will now be described. It

will be understood that the incubator which may be of any suitable or preferred construction comprises a plurality of superposed tiers, 31, 32, 33, each ordinarily containing a plurality of compartments and extending through each of which are radiating pipes P, P', the heater being preferably placed adjacent one end of the incubator, and a pipe 34 extended from the uppermost of the apertures 28 to connect with the pipe P of the lowermost tier 31, the pipe P', through which the heating liquid returns after passing through the several compartments, being connected with one of the openings 28' through a return pipe 35. Similarly, the pipe P of the intermediate tier 32 of the incubator is connected by a pipe 34' with one of the apertures 28 about midway between the top and bottom of the heater and the return pipe P' of that tier connected by a pipe 35' with another aperture 28' adjacent the base of the water reservoir, while the pipe P of the uppermost tier 33 is connected by pipe 34'' with an aperture in the face 26 relatively near the bottom thereof and the pipe P' of the upper tier through return pipe 35'' with an aperture 28'' adjacent the bottom of a reservoir, this latter aperture for convenience merely being shown at the back of the heater instead of adjacent the apertures 28'.

As incubators are frequently built with more than three tiers of compartments, I preferably provide the face 26 with several more apertures than those required to effect the connections just described, so that if a greater number of tiers are used these additional apertures may be employed for the necessary piping. Of course if they are not utilized these additional apertures will be closed with suitable plugs 38 as shown.

It will thus be observed that in the preferred form of installation the heating water as indicated by the arrows flows to the lowermost tier of compartments from a point adjacent the upper part of the water reservoir where the water is naturally the hottest and having given up its heat is returned to a point adjacent the bottom of the reservoir; that the water flows to the intermediate tier from a point about midway between the points where the water is hottest and coldest within the reservoir and is thus supplied to that tier at a little lower temperature than to the bottom tier, and that in a like manner the water supplied to the uppermost tier is taken from a point in the reservoir where it is of still lower temperature, the returns from all of the tiers being to the lower or coldest part of the reservoir. Under these conditions a substantially uniform temperature may be readily maintained in the several tiers, since the hottest water is supplied to the tier normally the coldest and the coldest water to the tier which is

normally the hottest, so that a very even and uniform temperature may be maintained in the different compartments in the several tiers, thus obviating constant opening or closing of the dampers or other heat controlling devices with which incubators of this class are ordinarily supplied and also resulting in a material saving of fuel over that consumed in the ordinary heating system in which it is necessary to maintain the water sufficiently hot to supply the requisite heat to the lowermost tier and to permit heat to escape from the upper tier to avoid overheating.

15 It has been found in practice that in order to satisfactorily maintain a fire for considerable periods of time in a water heater of the type ordinarily utilized for supplying hot water to incubators and the like, it is necessary to avoid undue restriction of the size of the fire pot, or, in other words, it is requisite to have the fire pot of sufficient size to contain a relatively considerable body of burning fuel, which of course results in 20 the giving off of a considerable amount of heat, with corresponding rise in temperature in the water in the heating reservoir, even with the fire reduced to the minimum at which it will remain alight. In consequence, when the water is conducted from the upper part of the water reservoir to a small incubator, such as one of the single deck type, the temperature of the incubator is raised beyond the desired point, it being 25 practically impossible on account of the size of the fire pot to supply the water at a sufficiently reduced temperature to produce the proper heating effect. An advantage of my improved form of heater, however, resides in the fact that under such conditions the water may be readily led to the incubator from a point adjacent the lower part of the heating chamber instead of from the upper part thereof and thus introduced to 30 the incubator at a lower temperature than is ordinarily possible with the forms of coal heaters hitherto in use, thus avoiding overheating of the incubator and assisting in maintaining a constant predetermined temperature therein.

40 While I have shown and described my invention in connection with a mammoth incubator having three tiers of hatching compartments it will be understood that it is equally applicable to incubators having a greater or lesser number of tiers, the piping in each case being so arranged that the water will be caused to flow from substantially the point in the heating reservoir where it is hottest to that tier of compartments which is normally the coolest and from a point in the heating reservoir where it is relatively cooler to that tier of compartments which is normally the warmest and to intermediate compartments from points in

the water reservoir between these two extremes, the return from all of the tiers being preferably brought to the same, on substantially the same, level adjacent the lowest point of the heating jacket, and I therefore 45 do not desire or intend to limit myself to the installation of the invention in connection with an incubator of any particular form or design or having any specific number of tiers or compartments or of compartments in a tier. Furthermore, while I have described with considerable particularity a preferred form of heater it will be understood that changes may be made in the details of construction and arrangement of the 50 parts thereof without departing from the spirit and scope of the invention as defined in the appended claims.

Having thus described my invention, I claim and desire to protect by Letters Patent of the United States:

1. A heating system for a mammoth incubator having a plurality of tiers of hatching compartments each tier having heat radiating means, comprising a heating unit 55 for supplying hot water and piping extending from the unit to the radiating means in each tier, said piping being so arranged as to convey the hottest water from the heating unit to the tier which is normally the coolest and relatively cooler water to the tier which is normally the hottest.

2. A heating system for a mammoth incubator having superposed tiers of hatching compartments each tier having independent heat radiating means therein, comprising a heating unit for supplying hot water and piping extending from said unit to each of said radiating means, said piping being so arranged as to convey the heating water 60 from a point in said unit where it is normally the hottest to the radiating means in that tier which is normally the coolest and to convey relatively cooler water from said unit to the radiating means in that tier which is normally the warmest.

3. A heating system for a mammoth incubator having superposed tiers of hatching compartments, comprising a heater for supplying heated water and piping extending 65 from said heater to each tier of compartments and arranged so as to convey water from substantially the highest point in the heating reservoir of said heater to that tier of compartments which is normally the coolest and to convey water from a lower point in said reservoir to that tier of compartments which is normally the warmest.

4. A heating system for a mammoth incubator having superposed tiers of hatching compartments each tier having independent radiating means therein, comprising a heater having a combustion chamber and a water jacket surrounding said chamber, a pipe extending from the upper part of said 70

1
jacket to the radiating means of the lowermost tier, a pipe extending from a relatively lower point in said jacket to the radiating means in the uppermost of said tiers and return pipes extending from each of said radiating means to a point adjacent the bottom of said jacket.

5. The combination with a mammoth incubator having superposed tiers of hatching compartments and heat radiating means in each tier, of a water heater having a water jacket surrounding a combustion chamber, a pipe extending from the upper part of said jacket to the radiating means in that

tier of compartments which is normally the coolest, a pipe extending from a relatively lower point in said jacket to the radiating means in that tier of compartments which is normally the warmest and return pipes extending from each of said means to a point adjacent the bottom of said jacket, whereby the hottest water will flow from said jacket through said first mentioned pipe and relatively cooler water through said second mentioned pipe. 15
20
25

In witness whereof, I have hereunto set my hand this 16th day of February, 1922.

HAROLD L. WATSON.
